UNITED STATES PATENT OFFICE.

SAMUEL D. SHEPARD, OF FRIENDSHIP HEIGHTS, MARYLAND, AND MAURICE SHAPIRIO, OF WASHINGTON, DISTRICT OF COLUMBIA.

GUN-SIGHT.

1,153,964.

Specification of Letters Patent. Patented Sept. 21, 1915.

Application filed February 16, 1915. Serial No. 8,675.

To all whom it may concern:

Be it known that we, SAMUEL D. SHEPARD and MAURICE SHAPIRIO, citizens of the United States, residing at Friendship Heights, in the county of Montgomery and State of Maryland, and Washington, District of Columbia, respectively, have invented certain new and useful Improvements in Gun-Sights, of which the following is a specification.

This invention relates to sighting appliances for firearms.

One object is to provide a sighting device for firearms embodying a front sight and a rear sight, the rear sight having a view slot divided vertically by a thin strip and the front sight including a horizontal portion adapted to be brought into alinement with said strip to provide an effective sighting point or line.

Another object resides in the provision of a sighting device embodying, among other characteristics, means whereby the firearm may be instantly thrown to different positions for any range desired, without necessitating the firer releasing the proper grip of either his left or his right hand with relation to the firearm when aiming and firing.

Another object is to provide a rear sight in the form of a metallic or other plate which embraces a code of range calculating openings adapted to be brought into coöperative registering relation with a front sight so as to judge the range or distance between the object to be fired at and the firer of the arm.

Another object resides in the provision of a sighting device for firearms embodying front and rear sights, the front sight having a horizontally disposed portion and the rear sight having a vertically disposed slot on one side of which and in spaced relation thereto and cut entirely through the metal of the rear sight is a series of spaced symbols indicative of different distances in alinement with which symbols the horizontal portion of the front sight is brought in the calculation of the distance it is desired to fire the arm.

A still further object resides in the provision of a firearm sighting device including a member provided with characteristics to facilitate judging distances without undue strain on the eyes of the firer and by the use of which efficient sighting may be accom-

plished in a dim light as well as a bright 55 light.

It is still further designed to provide a gun sighting device wherein a code embracing symbols indicative of different distances is employed, so that the firer, by memorizing 60 the symbols of the code, may easily and effectively position the gun for the range desired.

With the above and other objects in view the invention consists in the construction 65 and novel combination of parts hereinafter fully described, illustrated in the accompanying drawing, and pointed out in the claims hereto appended, it being understood that various changes in the form, proportion, size and minor details of construction, 70 within the scope of the claims, may be resorted to without departing from the spirit or sacrificing any of the advantages of the invention.

In the drawing: Figure 1 is a perspective view of a firearm illustrating the present invention applied thereto. Fig. 2 is a view of a firearm in aiming position, illustrating the present invention applied thereto. Fig. 3 80 is a detail view of the front sight. Fig. 4 is a view of the chart illustrating the different shaped symbol-openings indicative of different distances.

Referring now more particularly to the 85 accompanying drawings, there is illustrated a rifle or other firearm embodying a stock 10 and a barrel 11 at the outer end of which latter is secured in any suitable manner a front sight A of T-shape, having feet portions 12 by which it may be secured to the barrel 11, and a thin horizontally disposed head 13 connected at the top of its leg portion 14 and provided with windage projections 13^a and 13^b. The rear sight B is in 95 the form of a metal plate, slightly exaggerated in width for illustrative purposes, and this plate is preferably hingedly connected at 15 to the inner end of a barrel in any well known manner. This rear sight is provided 100 with a narrow longitudinal view slot 16 extending nearly throughout the length thereof, and which is preferably divided by a fine thin dividing strip 17.

Adjacent one side of the view slot 16 is 105 formed a series of openings 18, which are cut entirely through the plate and which openings are of different shapes, symboliz-

ing different objects, and which form part of a code whereby distances may be determined. These openings are spaced from one another and the space between them may be governed by ordnance requirements or suggestions. As shown in the chart C in Fig. 4, the opening 18 in the form of a square may indicate one hundred yards; the circle two hundred yards; the half circle 10 three hundred yards; the diamond-shaped opening four hundred yards; and so on throughout the chart. These peculiarly shaped openings are arranged for coöperation with the front sight A to judge the 15 range, it simply being necessary to bring the thin horizontal part 13 of the front sight A into alinement with the symbol denoting the distance judged by the firer. For instance, assuming that the distance it is desired to 20 cover were judged to be eight hundred yards, this would be indicated by the Maltese cross symbol. All the user has to do is to sight in accordance with the judged range, and to bring the thin horizontal portion 13 of the front sight A into horizontal 25 alinement with this Maltese cross opening, as shown in Fig. 2. On the side of the slot 16 of the sight B, opposite the side thereof on which the aforesaid openings 18 are 30 disposed, the sight B may have slots 19 to indicate distances between the openings 18.

When aiming at an object, the thin cross piece or head 13 of the front sight being arranged at a direct right angle to the aforesaid thin dividing strip 17, there is formed by said head and said strip a small sighting cross *a*, which is brought directly in front of the object to be fired at in the distance, obviating eye strain incident to sighting 35 through small apertures. When the sighting cross *a* is brought into play, the leg portion 14 of the front sight A is in direct alinement with the narrow strip 17, but on account of windage conditions, it may be 40 necessary to aline the strip 17 with either of the windage projections 13^a or 13^b, according to the direction of the wind, and as the wind has various velocities, it may not be necessary to shift the strip 17 into alinement with either of said projections, but 45 along the head 13 between the leg 14 and the adjacent projection, or, in the event that the wind be unusually strong, it may be necessary to aline the strip 17 with the 50 outer end of the head; that is, between the end of the head and the adjacent windage projection. During these various relations of the front and rear sights, the head or horizontal part 13 of the front sight is always 55 at a direct right angle to the strip 17 to form the sighting point, and the head of the front sight always assumes its proper relation with respect to the symbol openings in the rear sight.

60 The slot in the rear sight admits wide

view and the code symbols being arranged along either side of the slot and cut clear through the sight, and being of different shape, the range determining symbols are exceedingly clear to the firer's vision because they are readily distinguishable one from another, and because the light itself actually forms the symbols in that the light is seen through the symbol-openings, whereby the firer is enabled to gage the proper range in a dim light as well as in a bright light, without straining his eyes. Thus, the firer, in aiming the firearm, and also watching a moving target, is not compelled to both sight and read numerals inserted on the metal surface of the sight. On the contrary, in the present instance, the distance denoting symbol-openings stand out in great relief and enable the range to be had with accuracy and without danger of losing the proper range in quick action. By this peculiar form of sighting device, the firearm can be instantly adjusted to various distances without the firer releasing his proper grip of either left or right hand, an essential thing for aiming and firing. For illustration, a man shooting at a deer one hundred yards off, if he misses the deer on the first shot, his second shot would probably have to be at a greater distance, say, for instance, 95 two hundred yards. With the present device, the firearm can be instantly thrown into different positions for any range desired, making accurate allowances for trajectory, without releasing the proper hold 100 necessary for aiming and firing.

What is claimed is:—

1. The combination with a firearm, of a front sight of T-shape, and a rear sight provided with a longitudinal view slot and a vertical series of openings of different shapes which are indicative of different distances and each coöperative with the horizontal portion of the front T-shaped sight.

2. The combination with a firearm, of a front sight, and a rear sight provided with a view slot and a plurality of openings of different shape which are indicative of different distances and each coöperative with the front sight so as to facilitate positioning 110 of the gun for the range desired.

3. In a firearm, a front sight including a horizontal portion and a rear sight provided with a longitudinal view slot and a thin strip dividing the same and adapted to be brought into a visual intersection at various points along the horizontal portion of the front sight to form a sighting cross at such points of intersection.

4. A sighting member for firearms composed of a plate provided with a longitudinal view slot having smooth side edges and a series of openings spaced from said slot and indicative of different distances.

5. A sighting device member for firearms

composed of a plate provided with a longitudinally disposed view slot having smooth side edges and a series of openings of different shape spaced from said slot and indicative of different distances.

6. The combination with a firearm, of a front sight of T-shape, and a rear sight provided with a longitudinally disposed view slot divided throughout its length by a strip 10 adapted to be brought into registration with the front sight and also having a series of openings of different shape arranged in vertical alinement along one side of said slot in spaced relation to one another and to said 15 slot and which are adapted to coöperate selectively with the horizontal portion of the front T-shape sight.

7. A sighting device member for firearms composed of a plate provided with a divided 20 view slot and a series of alined openings in the plate on opposite sides of said slot and spaced therefrom, with each opening spaced one from another.

8. The combination with a firearm, of a front sight, and a rear sight provided with a view slot and a plurality of openings of different shape on one side of said slot, which are indicative of different distances and each of which is coöoperative with the 30 front sight, said rear sight having another series of openings on the opposite side of said slot which are coöoperative with the front sight so as to facilitate positioning of the gun for the desired range.

35 9. In combination with a firearm, of a front sight of T-shape and a rear sight provided with a longitudinal view slot and a thin strip dividing the same and adapted to align with the aforesaid front T-shaped sight.

40 10. The combination with a firearm, of a front sight including a horizontal portion, and a rear sight provided with a view slot divided by a thin strip adapted to coöperate with the horizontal portion of the front sight to provide for effective sighting from.

the point of visual intersection between the vertical strip and the horizontal portion of the front sight when they are alined.

11. The combination with a firearm, of a front sight of T-shape, and a rear sight provided with a longitudinal view slot and a thin strip dividing the same and adapted to coöperate with the aforesaid front T-shaped sight, the rear sight having a plurality of openings of different shape which are indicative of different distances and each coöoperative with the front sight so as to facilitate positioning of the gun for the range desired.

12. The combination with a firearm, of a front sight including a horizontal portion, and a rear sight provided with a view slot divided by a thin strip adapted to be brought into alinement with the horizontal portion 65 of the front sight to provide for effective sighting from the point of visual intersection between the vertical strip and the horizontal portion of the front sight when sighting, the rear sight having a plurality of 70 openings of different shape which are indicative of different distances and each coöoperative with the front sight so as to facilitate positioning of the gun for the range desired.

13. In a firearm, a front sight including a horizontal portion and a rear sight provided with a longitudinal view slot and a thin strip dividing the same and adapted to be brought into a visual intersection at various points along the horizontal portion of the front sight to form a sighting cross at such points of intersection, and windage projections depending from the horizontal portion of the front sight.

In testimony whereof we affix our signatures in presence of two witnesses.
